INVENTOR.

JOSEPH A. LALONDE
BY

Richard D. Dorn

ATTORNEY.

UNITED STATES PATENT OFFICE.

JOSEPH A. LALONDE, OF MONTREAL, QUEBEC, CANADA.

DISPLAY FORM.

Application filed July 29, 1926. Serial No. 125,758.

This invention relates to a display form and one which is particularly adapted for footwear and hosiery and which, when inserted into the same, will give a perfect display.

A particular object of the invention is to provide a display form which can be made of rubber and provided with an air valve so that the same may be inflated so that it will take the shape of the article into which it is to be inserted for display.

A further object of the invention is to provide a form which is portable and in storage can be reduced in bulk so that it will require small space and in transportation, thereby cutting down the expense and weight and size when the same has been deflated.

A further particular object of the invention is to provide a form which will effectively display shoes and hosiery as perfectly as if the same were on the natural foot and leg and one which is easy to insert and will not injure fancy shoes or very fragile hosiery.

A further object of the invention is to provide a display form which can be made in various fancy colors and sizes and which is washable and will not break with constant usage.

A still further object of the invention is to provide a display form, the walls of which are varied in thickness so that certain portions of the form can be used to effectively fill different sizes of articles, for instance, in the display of hosiery, while the leg sizes are substantially alike, variance in the foot sizes occur, even in stockings of the same size and my improved display form will fill out in the foot portions having thin

walls so that the entire article to be displayed will be effectively filled out and shown to advantage.

This is also true of the display form when used in shoes, where the strap portions and instep of the shoe are of slightly different contour and in this respect I have provided thin wall portions in the form whereby when the same is inflated, the thin wall portions will change the normal contour of the form to effectively fill out those portions of the shoe which do not conform to standard size.

In this respect, also, the form may be made so that the foot portion thereof is inflatable to greater size than the leg portion or upper part of the form so that the same will effectively fill different sizes of

shoes, thereby eliminating the necessity of having different size display forms for each different size of shoe.

To enable others skilled in the art to fully comprehend the underlying features of my invention that they may embody the same in the various modifications in structure and relation contemplated, a drawing depicting a preferred form has been annexed as a part of this disclosure and in such drawing, similar reference characters denote corresponding parts throughout all the views, of which,

Figure 1 is a view in side elevation, the same being shown in cross section of a shoe of the oxford type, the form being shown therein and also being shown in cross section to show how the same, when inflated will conform to the interior contour of the shoe and will effectively fill the same for display purposes.

Figure 2 is a view in side elevation of a stocking in which is inserted my improved hosiery display form showing how the same will fill out the stocking completely and effectively display it.

Figure 3 is a cross section in elevation of a modified form of shoe display form showing relatively thin wall portions formed therein so that these thin wall portions may protrude under inflation to effectively fill the shoe.

Figure 4 is a side view in elevation of a stocking form of modified construction, the walls thereof being relatively thin in some portions to provide, when the form is inflated, bulging portions which will effectively fill the foot or leg portion of the hosiery to display the same.

Referring to the drawings in detail 5 indicates a shoe of the oxford type, it of course being understood that this type of shoe is only shown for illustrative purposes and the form can be applied to any type of shoe or slippers or any other form of footwear, 6 indicates the usual heel portion and instep portion 7. The interior of the shoe is filled with my improved display form which comprises the resilient rubber wall 8, the form being shaped to provide the toe portion 9, heel 10 and instep 11. The upper part of the form is provided with an air valve 12, which consists of the usual spring pressed valve stem 13 and valve seat 14, it being of course understood that the walls of the display form being relatively thick may require

the inflation of the form through some means, such, for instance, as a small air pump, the end of which is shown in outline as at 15, which projects into the valve 12 5 to suitably depress the seat 14 to allow inflation of the form from the air pump, not shown.

It will be evident from inspection of Figure 1 that the interior of the shoe to be displayed is completely filled and the shoe assumes the shape that it would assume when worn on the natural foot and display thereof is complete and may be made to the best advantage.

15 This display form may be extended to provide a leg portion 16 over which may be drawn the stocking 17 and in this form, I provide in the top thereof, a suitable air valve 18 through the medium of which, the 20 form, itself may be inflated to effectively display the stocking 17 held thereon.

In shoes of various sizes and in which there may be some irregularity in shape or by reason of an enlarged strap portion, as 25 used in women's shoes, which embody cut-out designs, which are difficult of holding in proper position, I have provided an improved foot form in which the instep portion 19, heel portion 20 and toe portion 21 may 30 have relatively thinner walls than the remainder of the form so that when the form is inflated, the instep, toe and heel portion thereof will, under abnormal inflation of the form, protrude to fill up and effectively display any of the parts of the shoe, such, for 35 instance, as a broad, fancy, pierced instep strap as used on women's shoes.

40 In Figure 4 I have shown an additional modified form of display form which is used to fill out hosiery and which is provided in its foot portion with the thin walled instep 45 22 and heel 23, the thin wall portion being especially adapted to have an abnormal expansion when the form is inflated so that they will fill up the foot portion of the hosiery to effectively display the same.

It will be evident, therefore, that I have provided a foot display form which can be made up of rubber or other flexible, air-proof material and which can be inserted 50 into footwear, such as shoes, boots or fancy dress slippers and into hosiery whereby the same may be effectively displayed.

It is also evident that I have provided a display form which is easy to insert and 55 which, when deflated may be folded up for easy transportation or storage so that the space is reduced and also transportation and storage expenses.

It is also evident that I have provided a 60 foot form or hosiery form which can be made in various colors to match stockings or shoes in connection with which they are to be used and one which can be made to various sizes 65 to be used with different sized shoes and stockings.

It is also evident that I have provided a display form which may be washed and which is unbreakable and which will very effectively display hosiery and shoes in connection with which it is used.

While I have illustrated and described my invention with some degree of particularity, I realize that in practice various alterations therein may be made. I therefore reserve the 75 right and privilege of changing the form of the details of construction or otherwise altering the arrangement of the correlated parts without departing from the spirit of the invention or the scope of the appended claim. 80

Having thus described my invention, what I claim as new and desire to secure by United States Letters Patent is:—

A pneumatic hollow display form having a single resilient wall of unequal thickness at 85 predetermined locations in its construction, thereby causing the form to variably expand in the forcing of a fluid under pressure into the form.

In testimony whereof I affix my signature.

JOSEPH A. LALONDE. [L. S.]
